Attnys.

UNITED STATES PATENT OFFICE.

HUGH BULLOCK, OF ANDOVER, MASSACHUSETTS, ASSIGNOR TO CONVERSE RUBBER SHOE COMPANY, OF MALDEN, MASSACHUSETTS, A CORPORATION OF MASSACHUSETTS.

FOOTWEAR AND METHOD OF MAKING THE SAME.

1,356,961.

Specification of Letters Patent. Patented Oct. 26, 1920.

Application filed June 30, 1919. Serial No. 307,518.

To all whom it may concern:

Be it known that I, HUGH BULLOCK, a citizen of the United States, and a resident of Andover, in the county of Essex and Commonwealth of Massachusetts, have invented an Improvement in Footwear and Methods of Making the Same, of which the following description, in connection with the accompanying drawings, is a specification, like characters on the drawings representing like parts.

This invention pertains to improvements in footwear having rubber heels and methods of attaching said heels. The invention is of general application, but I have elected to disclose the same specifically in connection with the attachment of heels for rubber boots, though it is obvious that the invention may be of use in attaching rubber heels to other types of footwear.

In the drawings, which show a preferred embodiment of one form of my invention in connection with which I shall describe a preferred form of practising my improved methods:

Figure 1 is a side elevation of a rubber boot;

Fig. 2 is a plan of a heel for attachment thereto; and

Fig. 3 is a section on the line 3—3 of Fig. 2.

Rubber heels of a type adapted to be secured to footwear by rubber cement prior to complete vulcanization are ordinarily molded under pressure in a hot mold, preferably being partially vulcanized during the molding operation. The heels after removal from the mold are then usually coated on their upper surface with a rubber cement, and stuck to the coöperating parts, after which the shoe as a whole is vulcanized.

I have found that a marked saving in rubber cement may be effected and that the attachment of the heel 4 to the shoe 5 may be more readily effected and made more secure by applying a sheet of fabric 6 across the top of the heel. The application of this sheet of fabric is preferably effected during the molding of the heel, the fabric being pressed against the material forming the heel during the partial vulcanization thereof in the forming mold. The sheet of fabric may, for instance, be laid across the top of the mold prior to closure thereof by

the top platen, so that when the top platen 55 is pressed against the heel the sheet of fabric will be in effect consolidated therewith. The superior security of attachment and economy in cement secured by use of my invention is believed to arise not only 60 from the provision of the strip of fabric adjacent the surface to be cemented but also from the protection afforded by the fabric to the top of the heel during the semi-vulcanization, the rubber seeming to be cured 65 less adjacent the top when the fabric is applied than when the fabric is not applied. After the heel is molded with the fabric it may be secured to the coöperating parts of the shoe by a very thin layer of cement, 70 after which the usual vulcanization may complete the securing together of the parts. The cement may if desired be initially combined with the heel by utilizing for the fabric one frictioned with non-curing cement. During the partial vulcanization of the heel the fabric will prevent the sulfur from striking into the cement which will therefore be unaffected. When, however, the heel is secured in place the cement will 75 80 be cured by the sulfur in the main body of the shoe.

While I have shown and described one embodiment of my invention and one method of practising the same, it will be 85 understood that major changes involving omission, substitution, alteration and reversal of parts or materials may be made and that changes in the method may be effected within the scope of the following 90 claims:

1. The method of forming footwear of the class described, which comprises molding under pressure a heel of rubber or the like while pressing a sheet of fabric against 95 the top of the heel, subsequently securing said heel to the coöperating sole with said sheet of fabric adjacent the sole, and finally vulcanizing the parts thus assembled.

2. The method of forming footwear of 100 the class described which comprises molding under pressure a heel of rubber or the like while pressing a sheet of fabric against the top of the heel, semi-curing said material while in the mold and subsequently securing 105 said heel to the coöperating sole with said sheet of fabric adjacent the sole.

3. The method of forming footwear of

- the class described which comprises molding under pressure a heel of rubber or the like while pressing a sheet of fabric against the top of the heel, semi-curing said material 5 while in the mold, subsequently securing said heel to the coöperating sole with said sheet of fabric adjacent the sole and then finally vulcanizing the parts thus assembled.
4. The method of forming footwear of 10 the class described which comprises molding under pressure a heel of rubber or the like while pressing a sheet of fabric against the top of the heel, semi-curing said material while in the mold and subsequently se- 15 curing by rubber cement said heel to the coöperating sole with said sheet of fabric adjacent the sole.
5. The method of forming footwear of 20 the class described which comprises mold- ing under pressure a heel of rubber or the like while pressing a sheet of fabric against the top of the heel, semi-curing said mate-

rial while in the mold and subsequently se- 25 curing by rubber cement said heel to the coöperating sole with said sheet of fabric adjacent the sole and then finally vulcanizing the parts thus assembled.

6. The method of forming footwear of 30 the class described which comprises molding under pressure a heel of rubber or the like while pressing a sheet of fabric against the top of the heel which fabric is coated with non-curing cement, semi-curing said material while in the mold and subsequently se- 35 curing said heel to the coöperating sole with said sheet of fabric adjacent the sole.

7. As a new article of manufacture a heel 40 having a body portion of semi-cured rubber, a thickness of fabric on the inner face there- of and non-curing cement on the fabric.

In testimony whereof, I have signed my name to this specification.

HUGH BULLOCK.
